UNITED STATES PATENT OFFICE.

WILLIAM BIRSE, OF BRIDGEPORT, CONNECTICUT, ASSIGNOR TO BIRDSEY, SOMERS COMPANY, OF BRIDGEPORT, CONNECTICUT, A CORPORATION OF NEW YORK.

EXTENSIBLE CORSET CLASP OR STAY.

1,156,205.

Specification of Letters Patent. Patented Oct. 12, 1915.

Application filed July 30, 1914. Serial No. 854,084.

To all whom it may concern:

Be it known that I, WILLIAM BIRSE, a subject of the King of Great Britain, residing at Bridgeport, county of Fairfield, State of Connecticut, have invented an Improvement in Extensible Corset Clasps or Stays, of which the following is a specification.

This invention relates to clasps, stays, bones or steels, as they are variously termed, 10 for corsets, and has for its object to provide a clasp or stay extensible to adapt it for different lengths of corsets and comprising end members adapted to be secured in place in a corset and a central member to which 15 the end members are slidably attached so that when the wearer bends forward or sidewise, as may be, the clasps or stays, either or both, in addition to flexing in the usual manner will contract longitudinally, 20 that is to say the end members will slide inward relatively to the central members and will resume their normal position when the wearer stands erect again.

For convenience in illustration I have 25 shown the invention as applied to pairs of clasps, it being understood of course that the essential difference between clasps and stays is that the latter are not provided with clasp studs and eyes.

30 In the accompanying drawings forming a portion of this specification, Figures 1 and 4 are front views showing variant ways in which I have carried the principle of the invention into effect; Fig. 2 an edge view as 35 seen from the right in Fig. 1, and Figs. 3 and 5 are reverse views corresponding respectively with Figs. 1 and 4.

10 denotes the central members and 11 the end members of a corset clasp, the end 40 members being shown as provided with fastening elements, as studs 12 or eyes 13.

In the form illustrated in Figs. 1 to 3 inclusive the end members are slidably attached to the central member by means of 45 ways 14 shown as formed integral with the central member. These ways comprise simply side extensions of the central member which are turned over parallel with the member to form the ways which receive the 50 end members and permit them to slide freely. If preferred the central member may be simply a straight strip of spring

metal and the ways may be formed of separate pieces of metal and riveted or otherwise secured thereto.

In the form illustrated in Figs. 4 and 5, the end members are shown as provided near their inner ends with slots 15 and the central member is provided at its ends with 55 necks 16 which are slightly offset, to permit them to pass through the slots in the end members, and carry heads 17 which lie parallel with and are adapted to slide over the faces of the end members. As a means of retaining the members in alinement, the 60 central member is shown as provided with clips 18 which inclose the end members but permit them to slide freely. These clips are shown as separate strips of metal formed to 65 shape and riveted to the central member. 70 The end members are shown as provided near their ends with holes 19 to receive stitching as a means of securing said members to a corset.

When the wearer bends forward or side- 75 wise, wherever my novel clasps or stays are used, the end members will slide inward relatively to the central member, thus adding greatly to the comfort of the wearer, and will immediately resume their normal 80 position when the wearer assumes an erect position.

Another advantage of my novel clasp or stay is that it enables the manufacturer to dispense with some of the intermediate sizes 85 of clasps and stays as they may be extended or contracted within reasonable limits to adapt them to different lengths of corsets and still provide for ample sliding movement of the members when the body is bent 90 forward or sidewise.

Having thus described my invention I claim:

1. An extensible corset clasp comprising 95 end members having spaced apart fastening elements secured on one side, a central member in engagement with the other side of said members and provided at its ends with ways lying between certain of said fastening elements and adapted to receive the end 100 members and to permit the end members and corresponding fastening elements to slide freely relatively to said central member.

2. An extensible corset clasp comprising pairs of end members having spaced apart eyes and corresponding studs secured on one side, central members in engagement with the other side of said end members and provided with ways lying between certain of said eyes and studs respectively and adapted to receive the end members, where-

by the end members are permitted to slide freely relatively to the central members.

In testimony whereof I affix my signature in presence of two witnesses.

WILLIAM BIRSE.
